United States Patent Office

Des. 220,079
Patented Mar. 9, 1971

220,079

FILE HOLDER

Isak Benis, 2165 Matthews Ave., Bronx, N.Y. 10462

Filed Apr. 24, 1969, Ser. No. 16,887

Term of patent 3½ years

Int. Cl. D8—02

U.S. Cl. D8—94

FIG. 5 -

FIG. 1 is a perspective view of a file holder, associated with a file and another holder shown in phantom, showing my new design;

FIG. 2 is a side elevational view thereof;

FIG. 3 is an enlarged perspective view of the file holder;

FIG. 4 is a top plan view thereof; and

FIG. 5 is a bottom plan view thereof.

The phantom line disclosure of a file and another file holder is for illustrative purposes only.

I claim:

The ornamental design for a file holder, substantially as shown and described.
